UNITED STATES PATENT OFFICE.

JOHN A. McGLADE AND REUBEN C. TUSTIN, OF DONORA, PENNSYLVANIA; SAID TUSTIN
ASSIGNOR OF ONE-SIXTH OF THE ENTIRE RIGHT TO SAID McGLADE.

TELEPHONE-OPERATING MECHANISM.

Application filed August 15, 1925. Serial No. 50,346.

Our invention relates to telephone operating mechanism, which is used for the purpose of holding the receiver and operating the receiver-hook which makes the connection with the central office.

The object of our invention is, to provide means for operating a telephone without using the hands, leaving them free for use in writing and other purposes.

Our invention combines certain novel features and details of construction as will be more fully described hereinafter and finally pointed out in the claim.

We will now describe our invention, reference being made to the accompanying drawings, in which similar letters of reference indicate corresponding parts, and in which:—

Figure 1 is a side elevation of a telephone to which is attached by means of clamps B, a curved arm C, having an adjustable extension D, in its outer end to which is secured a telephone receiver E. The receiver is held in position on said extension D, by means of a clamp F.

Fig. 2 is a detail of the supporting means of the switch hook engaging lever, while

Fig. 3 shows spring means associated therewith.

Fig. 4 is a plan view of Fig. 1.

Secured on the arm C, is a support G, into which is pivoted an arm or lever H, one end of which is bent so as to lay out over the top of the receiver-hook I, and its opposite end is connected to a rod or wire J, which runs down to a foot-pedal K, hinged to the floor.

A spring L, is placed under the arm or lever H, at its pivotal point which causes the said arm or lever to normally press down on the top of the receiver-hook, thus holding said hook down when the phone is not in use.

A latch or dog M, is placed at one side of the foot-pedal K, for holding same down when the phone is in use.

A set-screw N, is located in the outer end of the arm C, for holding the extension in place after the same has been adjusted to

suit the operator or user of the phone.

We will now describe the operation of our invention, which is as follows:

Assuming that the several parts are in their normal position, that is the receiver-hook down and the pedal up. When it is desired to call the central, simply press the pedal down with the foot, which will pull the outer end of the arm or lever H, down and lift the inner end up off the receiver-hook, which movement will cause connection to be made with the central, after which you give the number wanted. When the pedal is down, the latch or dog will drop over the edge of the pedal and hold same in position until you have finished talking. When through, simply move the foot over against the latch or dog, pushing it off the edge of the pedal when same together with the arm or lever H, will be raised up at its outer end and tilted down at its opposite end which will press the receiver-hook down and break the connection with the party with whom you have been talking.

We are aware that many changes in the details of construction can be made without departing from the nature and scope of our invention.

Having described our invention, what we claim and desire to secure by Letters Patent is:—

A telephone operating mechanism consisting of a curved arm secured to a telephone by means of clamps and having secured in its outer end an adjustable extension for holding the receiver, a support secured to the curved arm into which is pivoted a lever one end of which rests on the receiver-hook and its opposite end being connected to a pedal by means of a rod or wire, together with a latch for holding said pedal down while in the operating position, all substantially as shown and for the purposes described.

In testimony that we claim the foregoing to be our own invention, we have hereunto set our hands.

JOHN A. McGLADE.
REUBEN C. TUSTIN.
